UNITED STATES PATENT OFFICE.

RICHARD GRAINGER NASH, OF LUCAN, NEAR DUBLIN, IRELAND.

BOTTLE FILLING AND STOPPERING MACHINE.

SPECIFICATION forming part of Letters Patent No. 714,511, dated November 25, 1902.

Application filed May 10, 1901. Serial No. 59,685. (No model.)

To all whom it may concern:

Be it known that I, RICHARD GRAINGER NASH, a subject of the King of Great Britain and Ireland, residing at Finnstown House, 5 Lucan, near Dublin, Ireland, have invented a certain new and useful Improved Bottle Filling and Stoppering Machine, (in respect whereof I have applied for a patent in Great Britain to bear date October 11, 1900, No. 18,128,) of which the following is a specification.

This invention relates to apparatus, hereinafter termed a "bottling-machine," for charging bottles or similar receptacles with 15 liquors—such as aerated waters, beers, wines, milk, &c.—and for stoppering or sealing such bottles or receptacles when so charged, the said apparatus being capable of employment with screw-caps, screw-stoppers, and other 20 sealing devices.

In the accompanying drawings, Figure 1 is a front elevation, and Fig. 2 a side elevation, of apparatus for charging bottles or similar receptacles constructed according to my improved method, Fig. 3 being an elevation of 25 a portion of such apparatus. Fig. 4 is a horizontal section through the filling-chamber, showing the controlling-valve and passages, Fig. 5 being a section on the line $x-x$ in Fig. 30 4. Figs. 6 and 7 are views of the stopper-holding jaws drawn to a larger scale.

The apparatus comprises a vertical frame A and a slide B, vertically movable in the frame A and to which longitudinal movement may be imparted by means of a hand-lever or, as shown in the drawings, by means 35 of a foot-lever C, the latter being connected to the slide B by a rod or link D. The charging nozzle or chamber E is pivotally and eccentrically mounted in bearings a, secured to the frame A, and is provided with crank-arms e, which, as shown in Fig. 3, engage with a recess b in the slide B, the extremity or charging-orifice e of the said nozzle being furnished 40 with packing material for making a joint upon the mouth of the bottle. The charging nozzle or chamber E may be provided with a snifting-valve F for releasing the pressure in the usual manner, this valve F being operated by the lever g pertaining to the valve G for admitting liquid to the charging nozzle or chamber E, the said lever for this purpose

carrying an adjustable rod g', adapted to engage a spring-pressed plunger g², which in turn actuates the rod f of the snifting-valve 55 F. The device for effecting the sealing of the receptacle is arranged above the charging-nozzle E and is also carried by or engaged with the slide B. It comprises a spindle H, supported in a vertical position by 60 and capable of longitudinal movement through fixed bearings H' H² and furnished with jaws or equivalent means for engaging with the screw cap or stopper. These jaws may consist of levers or arms h, pivoted 65 in lugs h', formed on or secured to the spindle H, the upper ends of the said levers h being forced outward by the action of a sleeve or collar I and returned by means of a spring or springs h². The sleeve I is "feathered" to the spindle H, so that while it may 70 be freely moved longitudinally thereon it cannot rotate independently of the said spindle. It is provided with a circumferential groove i, with which engages a fork b', secured to the slide B. Between the sleeve I and a collar h³, the latter being rigidly secured to the spindle H, is a spring h⁴, encircling the said spindle and serving to hold the upper ends h⁵ of the jaw-levers h firmly 75 against the sleeve, and thereby to close the stopper-grippers. When the foot-lever C is depressed, the sleeve I is raised in opposition to the spring h⁴, and the spindle H being prevented (owing to the collar h³ 80 abutting against the bearing H²) from ascending the stopper-grippers h are opened by their spring or springs h², ready for receiving a stopper which is held by the grippers as soon as the foot-lever C is released. 85 The spindle H may be operated rotatively 90 by means of bevel-gearing J J' or other suitable means. When bevel-gearing is used as shown in the drawings, the wheel J is feathered to the spindle H, so as to allow the latter to slide longitudinally through the said wheel. The bottle during the operation of filling and sealing is supported upon a platform K, carried by a bracket A', secured to the frame A of the machine. The platform 95 is secured to the upper extremity of a spindle k, a spiral or other suitable spring k' maintaining the platform at the desired height. The platform, which is preferably 100

recessed on the upper side for the reception of the bottle, may by means of a bell-crank or other lever K' be lowered for facilitating the introduction of the bottle.

5 The operation is as follows: Assuming that a bottle is to be charged with aerated water and to be sealed with a screw-cap, the foot-lever C being depressed, and consequently the nozzle or chamber E being in the charging position, as shown in Figs. 1 and 2, the platform K is lowered by means of the hand-lever K' and the bottle placed in position thereon. Upon the release of the said lever K' the bottle is raised by the spring k' until its mouth arrives against the charging-orifice e' , or the mouth of the bottle may be placed against the orifice e' and the platform K be then raised into contact with the bottom of the bottle. The supply-valve G is now opened 10 and the bottle charged. This is accomplished by drawing forward the lever g and imparting a rotative movement to the screwed spindle g^3 , which carries the valve G . The latter is thereupon unseated and the liquid and gas, 15 which have previously entered the chamber g^4 by way of the pipe g^5 , pass into the charging-nozzle E by way of the passage g^6 and thence through the orifice e' into the bottle, a further movement of the lever g bringing 20 the rod g' against and forcing back the plunger g^2 , and consequently through the latter and the rod f effecting the opening of the snifting-valve F , which is of ordinary well-known construction, and thus releasing the 25 pressure. The charging of the bottle having been effected, the slide B is lowered by the release of the foot-lever C . The charging-nozzle E is thus caused to move backward, as shown in dotted lines in Fig. 3, and to recede 30 from the mouth of the bottle out of the path of the rotating sealing device, so as to permit of the descent of the said sealing device. The cap gripped between the jaws h is thereby not only applied to the mouth of the bottle, but immediately screwed home. The 35 charged bottle may then be removed from the machine either by lowering the platform K by means of the lever K' or by raising the sealing device by means of the foot-lever C .

40 If desired, the motions of the several parts may be effected by means of suitably-timed cams or the like, the action of the whole apparatus being thus rendered automatic.

50 Where seals or capsules as distinguished 45 from screw-caps or screw-stoppers are employed, a rotative movement need not be imparted to the seal-applying mechanism. Its gripping action may, however, be utilized for closing the edges of the seal or capsule about 55 the mouth of the bottle.

What I claim as my invention, and desire to secure by Letters Patent, is—

60 1. A bottling-machine having a support for the vessel to be charged and a rotating and longitudinally-movable sealing device coaxial with the support, and a charging-chamber

movable into and out of a position in which its charging nozzle or orifice is coaxial with the sealing device and support, substantially as set forth.

70 2. A bottling-machine having a longitudinally-movable and rotatable sealing device and a charging-chamber movable into and out of a position in which its charging nozzle or orifice is coaxial with the sealing device, substantially as set forth.

75 3. In a bottling-machine, the combination, with a vertically-movable sealing device and a support adapted to hold the vessel to be charged with its mouth coaxial with the sealing device, of a charging-chamber pivoted so that it may be moved alternatively into the path of the sealing device with its orifice over the mouth of the vessel and out of said path and away from the vessel, substantially as set forth.

80 4. In a bottling-machine, the combination, with the fixed frame and a sealing device vertically movable thereon and a support adapted to hold the vessel to be charged with its mouth coaxial with the sealing device, of a charging-nozzle pivoted so that it may be moved in a vertical plane through a circular arc into and out of the path of the sealing device, substantially as set forth.

85 5. In a bottling-machine, the combination, with the fixed frame and a slide and vessel-support vertically movable thereon, of a vertically movable and rotatable sealing device and an eccentrically-pivoted charging-nozzle both in operative connection with the slide, substantially as set forth.

90 6. In a bottling-machine, the combination, with the fixed frame and a slide vertically movable thereon, of a vertically movable and rotatable sealing device and a charging-chamber pivoted to the frame and operatively connected with the slide so that, when the slide is moved, the charging nozzle or orifice is moved through a circular arc, substantially as set forth.

95 7. In a bottling-machine, the combination, with the fixed frame and a slide vertically movable thereon, of a vertically movable and rotatable sealing device, a charging-chamber pivoted to the frame and operatively connected with the slide, and charging and snifting valves for the charging-chamber both opened by the same operating device, substantially as set forth.

100 8. In a bottling-machine, the combination, with the fixed frame and a charging-chamber pivoted thereto so as to be capable of moving in a vertical plane, of charging and snifting valves for the chamber, the operating-lever of the charging-valve carrying an adjustable rod which, through a spring-pressed plunger movable in the fixed frame, opens the snifting-valve.

105 9. In a bottling-machine, the combination, with the fixed frame, a slide vertically movable therein, a charging-chamber eccentric-

ally pivoted to the frame, arms on the chamber engaging a recess in the slide, a rotating spindle above the charging-chamber, spring-pressed jaws pivotally connected to the spindle, and a spring-pressed sleeve slidable along the spindle and engaging extensions of the jaws and operatively connected with the slide, substantially as set forth.

In testimony whereof I have signed my name to this specification in the presence of 10 two subscribing witnesses.

RICHARD GRAINGER NASH.
